ADJUSTABLE OUTSIDE SUPPORT FOR
SHOE REPAIRING

Lee E. Payne, Clinton, Okla.

Application June 11, 1934, Serial No. 730,113

2 Claims. (Cl. 12—103)

This invention relates to supports for use in supporting and pressing a welt or other marginal projecting portion of a shoe against the margin of the sole which projects beyond a last located inside the shoe.

In the process of making welt shoes after the welt is attached and the inseam trimmed, a cork filling and cement are placed upon the insole to bring it up level with the inseam. Cement is then applied to the filling and to the welt and also to the inner face of the outsole. The outsole is positioned upon a shoe and the shoe placed in a sole laying machine which supports the shoe at the heel and toe portions and forces a yieldable pad against the outer face of the sole to press it firmly in contact with the shoe and hold it in position until the cement has set.

In sole laying machines used in the manufacture of shoes and in the resoling and half-soling thereof it is desirable to brace or sustain the extension of the shoe welt and sole during the cementing of the sole and the application of pressure to the bottom thereof without bending the extension over the edge of the last. Therefore in order to secure a close and uniform cement union between the welt and the sole and possibly between an additional extension element desired to be united with the margin of the tread sole, the extension must be sustained against the bottom pressure.

A primary object of this invention is to so construct an outside shoe support for use in connection with an inside last that the pressure exerted thereby on the welt will be equalized throughout its entire length, and any surface patch will be held closely in contact with the shoe upper.

Another object is to so construct an outside support for use in connection with an ordinary inside last, said outside support being designed to hold the patch or the shoe and the welt in place during the cementing and which support is adjustable to fit shoes of different sizes and those having different shaped toes.

Still another object is to provide an adjustable support of this character the parts of which are held against slipping during the adjustment and use of the support.

Still another object is to provide a sectional welt-gripping support which may be nicely adjusted to fit the shoe to be repaired and the parts then rigidly locked together to move as a single unit when pressure is exerted thereon by the screw of the cement press.

Another object is to provide a welt-sustaining platen having a continuous welt-engaging sur-

face formed and arranged to extend around the heel, on both sides and to the toe, at which latter point the platen is divided or formed in sections adapted to be moved toward and away from each other to accommodate shoes of different widths, a bridging plate being provided between the sections at the toe where the sections do not come together to prevent curling of the welt at this point.

In operating upon shoes of the Goodyear welt type the sustaining means would bear on the welt-strip, while in operating on shoes of other types it would bear on the shoe element that occupies the position corresponding to that of a welt-strip. Therefore, for convenience of expression and without implying any limiting significance other than that of location, such terms as "welt" and "welt-portion" are used in their broadest sense in the following description and claims.

These and other features of the invention, including new and important details of construction and combination of parts, will be hereinafter more particularly described and claimed.

In the drawings Figure 1 represents a side elevation of the support embodying this invention, shown applied, with the sole pressure pad in section;

Fig. 2 is a bottom plan view thereof;

Fig. 3 is a transverse section taken on the line 3—3 of Fig. 2;

Fig. 4 is a detail section taken on the line 4—4 of Fig. 2;

Fig. 5 is a top plan view;

Fig. 6 is a side elevation of a slightly different form of the invention shown applied, and

Fig. 7 is a bottom plan view thereof.

In the embodiment illustrated in Figs. 1 to 5 an inside last L such as is usually used with cementing machines or presses, is shown inserted in a shoe upper U and has a central upstanding member L'. This last L bears against the insole of the shoe and cooperates with the outer support constituting this invention for holding or sustaining the shoe welt W and the extension of the sole S during the application of pressure to the bottom of the sole S by the pad P.

The outer support constituting this invention comprises two sections 1 and 2 for engaging and fitting around opposite sides of a shoe, around the heel and extending to the toe. These sections may be made of any suitable material preferably of aluminum and just heavy enough to withstand the necessary pressure without springing. As shown in Fig. 3 the sections 1 and 2 are hollowed

or shaped to fit over and snugly embrace the sides of a shoe upper U with the lower edges 4 of said sections tapered or made wedge-shaped to fit between the upper U and the welt W and to 5 bear on the outer face of the welt throughout its width. A piece of felt 3 or other suitable material is designed to be inserted between the support and the shoe upper to prevent marring of the upper, while cementing the patch thereto.

10 The sections 1 and 2 have upstanding side members 5 and 6 spaced laterally apart and equipped on their inner faces with longitudinally extending corrugations 7 for interlocking engagement with similar corrugations 11 on opposite 15 sides of a vertically movable central member 10 whereby said members 5, 6 and 10 are held in adjusted relation during the tightening of a bolt or screw 8 extending thru members 5 and 6 and thru slots 12 in said member 10. This central member 10 has a longitudinally extending cut-out 20 portion 13 in its lower face to fit over the upstanding member L' of the inside last L.

The front ends of the support sections 1 and 2 are normally spaced apart as shown in Figs. 2, 5 25 and 7 to adapt them to be adjusted toward and away from each other to fit shoe toes of different shapes and shoes of different widths. Between the front ends of these sections 1 and 2 is designed to be fitted a plate 15 substantially U or 30 horse-shoe shaped as shown in Fig. 2 and which is placed under the front ends of the support sections 1 and 2 between them and the welt W. This plate 15 is made thicker at the central portion as shown at 16 and tapers towards the ends 35 17 and is sufficiently heavy to prevent the shoe welt from springing up or curling while it is in the press. Any desired number of these plates 15 may be provided, being of different sizes and shapes for use in soeling shoes of different sizes 40 and having different shaped toes.

In the use of this support the shoe to be patched, soled or half soled, as the case may be, is placed on the inside last L in the usual way. Then this cooperating outside support has its 45 sections 1 and 2 fitted around the shoe with their knife-edges 4 inserted in the groove between the welt W and the upper U as is shown clearly in Fig. 3 with a piece of felt or other suitable material 3 arranged between the upper face of the 50 upper and the support to prevent marring of the upper. The bolt 8 is inserted thru the sections 1 and 2 or rather thru the upstanding portions 5 and 6 thereof. Then the central adjusting member 10 is inserted between the members 5 and 6 55 with its cut-out portion 13 straddling the upstanding member L' of the inside last and its slots 12 straddling the bolt 8. The corrugations 11 of member 10 engage the corrugations 7 of section members 5 and 6 and lock the parts in adjusted position, holding them securely while the bolt 8

has its nut tightened up to force them in tightly clamped relation.

When the parts have been so assembled and the sole S with the cement on its inner face laid on the welt as shown in Fig. 3 the pressure pad P, 5 here shown in the form of a water bag, is placed under the sole or the sole placed on it. Then the screw 18 carried by the cement press is engaged with the central support member 10 and screwed down forcing the assembly down on the pressure 10 pad P where it is held until the cement sets or cures, and thus reliably and uniformly cements the sole to the welt.

A cement press is not needed when this machine is used to hold a patch in place upon the 15 upper of a shoe; because sufficient pressure can be applied by bolt 8 and its nut 9.

Figs. 6 and 7 illustrate a modified form employed in repairing shoes when a "half sole" is 20 to be put on.

Sections 1a and 2a extend from the "shank" of the shoe, on one side, forwardly and around the toe to the "shank" of the shoe on the other side. The same cooperating inside last L employed in the form shown in Figs. 1 to 5, inclusive, is used 25 in the form of support shown in Figs. 6 and 7 and the same character of bridging plates 15a are used.

When necessary or desirable sections 1 and 2 and 1a and 2a may be made in rights and lefts 30 to conform with the peculiar contours of the shoes to be repaired. It is desirable that the cooperating sections fit the shoe snugly, to get best results; but inequalities in contours, if not too pronounced, may be built up or filled in by pieces 35 of felt 3.

I claim as my invention:

1. In a machine of the class described perforated complementary welt-gripping elements in combination with a central spacing member having a transverse slot extending vertically therein, and a bolt to pass through the perforations and the slot to tightly clamp the welt-gripping elements and the central spacing member together. 40

2. In an adjustable outside support for shoe repairing the combination of two cooperating sections having their inner faces formed to fit the contour of a shoe and contact and snugly surround and engage therewith, the lower part of each section presenting a wedge-shaped inwardly 45 projecting portion to enter between the upper and the welt of a shoe, an adjustable central spacing member between the sections having corrugations on its sides, cooperating corrugations on the sections and means for drawing together 50 the sections whereby the corrugations on the central spacing member and on the sections interengage and hold the central spacing member and the sections rigidly in adjusted position to move as a unit. 55
